UNITED STATES PATENT OFFICE.

CHARLES FALL AND FREDERICK PAULL, OF ESSEXVILLE, MICHIGAN.

LATCH LIFTER FOR FREIGHT-CAR COUPLERS.

Application filed January 27, 1925. Serial No. 5,081.

This invention relates to freight car couplers. The improvement pertains more particularly to a mechanical means for lifting the latch of a car coupler of that type wherein a horizontal crank shaft is secured to the end of the car and a pivoted link connects the crank with the coupler latch to be lifted.

Our invention resides to an improved link construction.

The objects are to provide a link which in its form and appearance is substantially the same as the solid or one-piece link which is at present commonly employed, and to improve the construction of the upper end of the link which has heretofore been made of a solid piece formed with a hole through which the crank pin was passed.

The advantage of our improvement will be apparent when the conditions are set forth under which coupler repairs are made in railroad shops.

Couplers, as is well known, are bolted to the under side of the car frame and they frequently have to be repaired and the bolt connections replaced. A car coupler is heavy and consequently it must first be supported while being unfastened from the car frame, and then lowered by means of jacks while the frame is being repaired. Afterwards it is jacked up into position and bolted. It is, of course, necessary to disconnect the latch-lifting link from the operating crank.

Various types of detachable links have been employed, whereby the connection between the coupler latch and the lifting crank can be quickly unfastened, but with the solid type of approved link, which is made in one piece and has an eye or hole that receives the crank pin, there is no means of quickly and easily detaching the coupler from the crank shaft. Consequently, it becomes necessary with such types of coupling devices to unfasten all of the crank shaft bearings from the end of the car before the coupler can be lowered, and to bolt the bearings in place again when the coupler is raised. These operations require two or three hours of the time of a crew of repair men, and is expensive.

Our improvement, which has to do with the construction of the upper or eye-end of the link, provides means for easily and quickly detaching the latch-lifting link from the crank by merely removing one small

pin, yet the size, form and general appearance of the link itself is the same as that commonly accepted as standard on freight cars at the present time.

Our separable lifting link, although preferably of the same shape and size as the standard solid link is of substantially equal strength, to withstand endwise pull and edgewise shocks, with the solid or closed eye type of link heretofore employed.

With the foregoing and certain other objects in view which will appear later in the specifications, our invention comprises the devices described and claimed and the equivalents thereof.

In the drawings Fig. 1 is a diagrammatic view showing the end of a freight car with a latch-lifting link and crank shaft of the type to which our improvement is adapted.

Fig. 2 is a side view of our improved link.

Fig. 3 is a fragmentary edge view as seen in the direction of the arrow, Fig. 2.

Fig. 4 is a top plan view of the parts shown in Fig. 2.

Fig. 5 is a detail, partly broken away, showing the movable jaw arrangement.

As is clearly shown in the drawings, 1 is the usual car coupler with its locking latch 2, which may be of any suitable construction, and 3 is the link by which the latch 2 is lifted. 4 indicates the crank, and 5 the crank shaft with its handle 6. The crank shaft is supported by the usual boxes or bearings 7 bolted to the end of the car body. The lower end of link 3 is provided with laterally projecting lugs 8 that form a pivotal connection between the link 3 and the latch 2, indicated by dotted lines in Fig. 2.

Heretofore, as above stated, the eye 9 has usually been made solid and the crank pin passed through it, as a permanent assembly. In our improved construction, however, we divide the link at its eye and thereby provide a pivoted jaw 10 which is secured by a pivot pin 11 to the link 3. 12 is a fixed jaw. The link is bifurcated, as at 13, to receive the lower end of the pivoted jaw 10, and a tongue 14 is provided at the free end of jaw 10 adapted to be received in a slit 15 of the fixed jaw 12, as shown in Fig. 4. Jaw 10 is pivoted on a suitable pin passed through the holes 16. The lower end of jaw 10 is formed with a curved or rounded shoulder 17, which takes against a corresponding concave seat 18 on link 3. This shoulder and

seat, when in engagement and held in place by the pin 11, lock the jaw 10 to prevent its being pulled out endwise. The engaged shoulders relieve the pivot 11 of strain, so that the eye formed by jaws 10 and 12 is virtually as strong as that of the solid-eye lifting link heretofore employed.

Similarly the interlocking tongue 14 and bifurcated end of the fixed jaw 12 impart such strength to the eye that for practical purposes this eye, which can be opened, meets all the requirements of standard specifications for a one-piece link, having an eye that can not open.

15 The pivot pin 11 and the pin through holes 16 are subjected to practically no strain while link 3 is in use. Yet the removal of the upper pin from holes 16 allows jaw 10 to open, immediately disconnecting 20 the link from the crank pin and avoiding the necessity of removing all of the shaft bearings in order to repair the coupler or its supporting bolts and frame.

By the means above described we have 25 provided a quick-opening link that is simple and inexpensive to manufacture, yet con-

forms to the specifications for closed links and does not materially depart from the shape, size or appearance of such links, already in use.

Having thus described our invention, what we claim and desire to secure by Letters Patent is:

In combination with the lifting crank and liftable lock in a D-type coupler, a latch-lifting link having an eye structure consisting of a fixed jaw, a pivoted jaw, a bearing member on said fixed jaw, a shoulder on said movable jaw adapted to engage said bearing member to prevent relative longitudinal movement of said jaws when in closed position, the outer ends of said jaws having tongue-and-slot interlocking means, said eye structure comprising an uncoupling device adapted to disconnect said lifting crank and said link to permit removal of said coupler independent of said crank.

In testimony whereof, we affix our signatures.

FREDERICK PAULL.
CHARLES FALL.
